Application May 29, 1945, Serial No. 596,514

10 Claims. (Cl. 74—9)

1

The present invention relates to engine starters and more particularly to starter gearing of the type in which a pinion is automatically traversed into and out of mesh with a gear of the engine to be started.

It is an object of the present invention to provide a novel engine starter drive in which the pinion is traversed into mesh with the engine gear by a small initial rotation of the starting motor whereby only a slight amount of kinetic energy is stored up in the rotating parts, and a small cushioning means is adequate to absorb the shock of engagement.

It is another object to provide such a device comprising novel means for insuring proper meshing engagement of the pinion with the engine gear.

It is a further object to provide such a device comprising novel means for preventing the pinion from drifting into undesired engagement with the engine gear.

It is another object to provide such a device including an overrunning clutch connection to the pinion, and means for holding the pinion in mesh with the engine gear until the engine is reliably self-operative.

It is another object to provide such a device in which the holding means for the pinion may be manually and/or centrifugally controlled.

Further objects and advantages will be apparent from the following description taken in connection with the accompanying drawing in which:

Fig. 1 is a side elevation partly in section of a preferred embodiment of the invention;

Fig. 2 is a section taken substantially on the line 2—2 of Fig. 1;

Fig. 3 is a view similar to Fig. 1 showing the parts in operative or cranking position;

Fig. 4 is a rear end view of Fig. 1;

Fig. 5 is a detail in perspective of the control member and pinion illustrated in Figs. 1 and 2, shown in disassembled relation;

Fig. 6 is a detail in perspective of the enclosing barrel member shown in Figs. 1 and 2;

Fig. 7 is a side elevation partly in section of an embodiment of the invention incorporating means for positively holding the pinion in mesh, only the drive end of the starting motor being illustrated;

Fig. 8 is a similar view of the opposite end of the starting motor of the embodiment shown in Fig. 7 illustrating the starting switch and electromagnetic actuating means, the remaining elements of the starting system being shown diagrammatically;

2

Fig. 9 is a view similar to Figs. 7 and 8, showing the parts in operative or driving position, the motor being shown only in a fragmentary manner in order to allow the parts of the starter drive to be shown more clearly;

Fig. 10 is a detail in perspective of the barrel and clutch member shown in Fig. 9;

Fig. 11 is a section taken substantially on the line 11—11 of Fig. 9;

Fig. 12 is a side elevation partly in section of a third embodiment of the invention in which the pinion is arranged to travel outwardly away from the starting motor into mesh with the engine gear;

Fig. 13 is a side elevation partly in section of the drive shown in Fig. 12, with the parts in cranking position;

Fig. 14 is a detail in perspective of the driving and traversing sleeve shown in Figs. 12 and 13 with its set screw and detent pin shown in disassembled relation; and

Fig. 15 is a section taken substantially on the line 15—15 of Fig. 12.

In Fig. 1 of the drawing there is illustrated a motor 1 having an extended armature shaft 2 and a pinion 3 slidably journaled on the shaft for longitudinal movement into and out of mesh with a gear 4 of an engine to be started. A control member 5 for the pinion is also slidably journaled on the power shaft 2 and is provided with

diametrically arranged inclined slots 6 and 7 (Figs. 2 and 5) which slidably receive the ends of a pin 8 fixedly mounted in the power shaft 2 whereby relative rotation of the control member 5 on the shaft causes longitudinal movement of the control member.

Means for connecting the pinion for longitudinal movement with the control member is provided in the form of a spring 9 interposed between

said members, and a barrel member or casing 11. The barrel is attached at one end to the hub 12 of the pinion as by means of an in-turned flange 13 bearing in a groove 14 in said hub, and the other end of the barrel is spun over

the end of the control member 5 as shown at 15 so as to limit the separation of the control member and pinion and maintain the spring 9 under initial compression. The barrel member 11 is non-rotatably connected to the control member 5 as by means of a rib or dimple 16 which is forced into a groove 17 in the control member as shown in Figs. 1 and 2.

The pinion 3 is connected positively to rotate with the control member 5 by cutting away the hub of the pinion to form tongues 18, and 19

(Fig. 5), and by forming a diametral slot 21 in the end of the control member adapted to slidably receive said tongues.

According to the present invention, the inclined slots 6 and 7 in the control member are so formed as to secure the traversal of the pinion into mesh with the engine gear after only a very small amount of rotation of the control member on the power shaft. This prevents the building up of any substantial amount of kinetic energy in the rotating parts prior to the engagement of the pin 8 in the ends of said slots, so that said engagement takes place, and the cranking load is assumed, without objectionable shock. This result is accomplished by forming the portions of the slots 6 and 7 occupied by the pin while in idle position at a small angle to the plane of rotation for a sufficient distance to secure initial entry of the teeth of the pinion 3 into the tooth spaces of the engine gear while the remainder of the slots are inclined steeply to the plane of rotation whereby traversal of the control member and pinion is greatly accelerated, such traversal being insured by the fact that rotation of the pinion at this time is prevented by its engagement with the engine gear.

When the initial inclination of the slot is made about 20° from the plane of rotation, and the steeper portions of the slots are inclined at about 70° to the plane of rotation, it has been found possible to secure the desired traversal of the pinion by rotation of the control member on the power shaft through about 60°. The kinetic energy of the rotating parts is thereby prevented from building up to a substantial amount prior to assumption of the cranking load, so that little, if any, cushioning means are required to secure satisfactory operation. In order to secure quiet operation of the drive, however, it is preferred to utilize small cushioning means in the ends of the slots 6 and 7 to receive the impact of the ends of the pin 8 thereon. As shown in Fig. 5, these cushions are in the form of blocks 22, 23 seated in enlargements 24, 25 in the ends of the slots 6, 7 and formed with hollow cylindrical surfaces 26 for receiving the ends of the pin.

The pin 8 is locked in the motor shaft 2 by means of a stud 27 threaded in the end of the shaft and provided with a conical point 28 engaging in a corresponding recess 29 in the side of the pin. The stud 27 also serves as a mounting means for anti-drift spring 31 which is clamped on the end of the motor shaft by the head 32 of the stud and has elastic arms 33 and 34 which are arranged to engage yieldably in notches 35, and 36 in the end of the control member, so as to resist rotation of the control member away from idle position. The sides of the notches 35, 36 are preferably beveled at about 45° as shown so as to cam out the arms of the anti-drift spring when sufficient rotational force is applied.

In the operation of this embodiment of the invention and starting with the parts in the positions illustrated in Fig. 1, acceleration of the power shaft 2 by the starting motor causes the control member 5 to free itself from the anti-drift spring 31, by virtue of the rotational inertia of the unit of which it forms a part, and to be traversed by the travel of the pin 8 in slots 6, 7 so as to move the pinion 3 into mesh with the engine gear. If tooth abutment should occur between the pinion and the engine gear, the movement of the pinion is momentarily arrested thus compressing the spring 9. Torque is there-

by built up by the rotary component of force transmitted to the control member by the pin 8 whereby the control member and pinion are rotated to index the pinion into proper registry with the tooth spaces of the engine gear whereupon the spring 9 expands and snaps the pinion into initial mesh and the meshing movement proceeds until arrested by the engagement of the pin 8 in the ends of the slots 6, 7, such engagement being cushioned by the rubber blocks 22, 23. The control member and pinion are thereupon constrained to rotate with the power shaft thus rotating the gear 4 to crank the engine. When the engine starts, the acceleration of the pinion 3 is transmitted to the control member 5 causing it to be traversed back to idle position where it is retained by the detent action of the anti-drift spring 31.

In Figs. 7 to 11, inclusive, of the drawing, there is illustrated an embodiment of the invention in which the driving pinion is positively held in mesh with the engine gear by a locking means which is under the control of the operator.

In Fig. 7 of the drawing there is illustrated a starting motor 50 having a hollow armature shaft 51 on which is slidably journaled a pinion 52 adapted to be moved into and out of mesh with a member such as a gear 53 of an engine to be started. A control member 54 for the pinion is also slidably journaled on the shaft 51 and is provided with radial slots 55 and 56 which are inclined to the axis of the member as best shown in Fig. 10. A pin 57 extends diametrically through the shaft 51 with its ends slidably engaging in the slots 55, 56 of the control member whereby relative rotation between the shaft and control member causes longitudinal movement of the control member. The pin 57 is fixed in the shaft 51 by means of a stud 58 threaded into the end of the shaft and having a conical point 59 entering a corresponding recess 60 in the pin.

Means are provided for rotating the pinion 52 from the control member 54 and for moving the pinion longitudinally therewith. As here shown this means comprises a clutch member 61 splined on the hub 62 of the pinion, being retained thereon by a ring 63 fixed on the hub in any suitable manner as by swaging or upsetting the hub as shown at 64. A spring 65 is arranged to yieldingly hold the clutch member 61 against the retaining ring 63. The control member 54 is enlarged as indicated at 66 and is provided with a circular series of recesses 67 (Fig. 11) having cam surfaces 68, and clutch rolls 69 are located in said recesses and cooperate with said cam surfaces to form an overrunning clutch connection between the control member 54 and the driven clutch member 61. The clutch member 61 is retained in the enlarged portion 66 of the control member by means of an annular plate 70 attached to said control member by swaging or spinning over a lip 71 thereof.

Means for holding the control member in idle position is provided comprising an anti-drift spring 72 which is clamped on the end of the power shaft 51 by means of the stud 58, the ends of said spring being arranged to enter notches 73 and 73' formed in the end of the control member as best shown in Fig. 10.

The interior of the control member has an annular recess 74 formed therein providing an inclined shoulder 75. A detent pin 76 is mounted in the shaft 51 with freedom for radial sliding movement, and is provided with a head 77 so lo-

cated and formed as to engage with the inclined shoulder 75 of the control member when the pinion is in mesh with the engine gear 53 as shown in Fig. 9. The head 77 of pin 76 is enlarged with respect to the remainder of the pin whereby centrifugal force causes the pin to enter the recess 74 and engage the shoulder 75 when the shaft 51 is rotating.

Means under the control of the operator for applying radial pressure to the head 77 of pin 76 to cause it to engage the control member 54, and to hold the pin in engagement with the shoulder 75 is provided in the form of a plunger 78 which is slidably mounted in the shaft 51 and is beveled on its end so as to engage the correspondingly beveled inner surface of the head 77.

In the present invention a starting system is provided which incorporates a unitary electro-magnetic means for energizing the starting motor and at the same time causing force to be applied to the plunger 78 to urge it toward operative position. As shown in Fig. 8, the starting system comprises a battery 79 grounded at 80 and connected by a lead 81 to a starting switch comprising fixed contacts 82 and 83 and a bridging contact 84. A lead 85 connects the starting switch to the live terminal 86 of the starting motor, the motor being grounded at 87 to complete the starting circuit. Electro-magnetic means for actuating the starting switch is provided comprising a solenoid 88 connected by a lead 89 and manual switch 90 to the battery lead 81, and grounded at 91 to complete the solenoid circuit. The core 92 of the solenoid carries the bridging contact 84 of the starting switch on one end, and at its other end has connected thereto in any suitable manner a rod 93 which terminates in a head 94 slidably mounted in a recess 95 in the plunger 78 and retained therein in any suitable manner as indicated at 96. A compression spring 97 is located in the recess 95, to yieldably transmit thrust from the rod 93 to the plunger, a ball bearing 98 being preferably interposed to reduce friction.

The starting switch and the electro-magnetic actuating means are preferably mounted on the end of the starting motor 50 as by means of a suitable casing 99 attached thereto as indicated at 100 whereby the core 92 of the solenoid is located in position to receive the end of the rod 93 as it projects axially from the motor shaft 51.

Means for yieldably holding the starting switch open and the plunger 78 in retracted position is provided in the form of a light spring 101 bearing against a partition 102 in the starting switch casing, and urging the core 92 away from its centered relation with respect to the solenoid, 88.

In the operation of this embodiment of the invention, closure of the manual switch 90 by the operator causes energization of the solenoid 88 thus closing the starting switch and at the same time moving the rod 93 to apply pressure through the spring 97 to the plunger 78. The rotation of the power shaft 51 causes the ends of the pin 57 to traverse the inclined slots 55, 56 of the control member 54 thereby advancing the control member, and consequently moving the pinion 52 into mesh with the engine gear 53. If tooth abutment should occur between the pinion and engine gear, the spring 65 will be compressed until initial rotation of the control member is transmitted through the rollers 69 and driven clutch member 61 to the pinion, indexing it into proper registry with the tooth spaces of the engine gear whereupon the spring 65 expands and

the meshing movement of the pinion continues until arrested by engagement of the pin 57 with the ends of the slots 55, 56.

When the control member 54 has traversed sufficiently to move the pinion into its fully meshed position, the recess 74 in the control member is brought into registry with the detent pin 76 in the power shaft, whereupon the pin is moved outwardly by the camming effect of the plunger 78 as actuated by the expansion of the spring 97. Thereafter the engagement of the detent with the inclined shoulder 75 prevents retrograde motion of the control member 54 as long as the starting switch is held closed.

When the pin 57 engages the ends of the slots 55, 56 in the control member, the parts are constrained to rotate in unison, and this rotation is transmitted through the clutch rollers 69 to the clutch member 61 and pinion 52 whereby the engine gear 53 is rotated to crank the engine. When the engine starts, the acceleration of the engine gear causes the pinion 52 to be rapidly accelerated but this rotation is not transmitted to the armature of the starting motor by reason of the disconnection of the overrunning clutch 66, 69, 61. If the engine should not remain self-operative, cranking will be resumed as soon as the rotational speed of the pinion 52 by the starting motor equals that of the engine gear. When the engine has become reliably self-operative, the operator opens the manual switch 90 thus deenergizing the solenoid 88 whereupon the starting switch 82, 83, 84 is opened, and the plunger 78 is retracted by the expansion of spring 101.

The deceleration of the power shaft 51 caused by the deenergization of the starting motor, together with the rotational drag transmitted to the control member 54 from the pinion 52 through the overrunning clutch tends to return the control member to idle position which action is permitted by the detent 76 as soon as the rotation of the armature shaft has slowed down sufficiently to reduce the effect of centrifugal force thereon. When the control member reaches idle position, the ends of the anti-drift spring 72 engage within the recesses 73, 73' on the end of the control member and yieldingly resist rotation of the control member away from idle position.

It has been found in practical use of this embodiment of the invention that when the slots 55 and 56 in the control member 54 are formed in the manner set forth in the description of the first embodiment of the invention, the operation of the drive is satisfactory without the incorporation of any cushioning means in the ends of said slots. If deemed desirable, however, such cushioning means may be incorporated as illustrated in Fig. 10 in the form of blocks 103 of elastically deformable material seated in enlargements in the ends of the slots and formed to receive the ends of the pin 57 and thereby arrest the meshing movement of the control member.

A sleeve 104 is preferably mounted on the exterior of the control member 54 to enclose the parts and to assist in retaining the cushioning blocks 103 when such are employed. This sleeve may be fixed on the control member in any suitable manner as indicated at 105.

In Figs. 12 to 15 of the drawing there is illustrated an embodiment of the invention of so-called "outboard" type in which the pinion moves outwardly away from the starting motor when it engages the engine gear. As there shown, a hollow armature shaft 110 extends outwardly from the end bearing 111 of the starting motor

and is supported at its outer end by a bearing 112 formed in an outboard housing member 113 attached to the motor casing as shown at 114. A pinion 115 is slidably journaled on the power shaft 110 for movement toward the bearing 112 into mesh with a gear 116 of an engine to be started.

A sleeve 117 is fixed on the power shaft 110 in any suitable manner as by means of a key 118 and set screw 119 (Fig. 14), said sleeve being provided exteriorly with inclined grooves 120, 121. A control member 122 is journaled on the sleeve 117 and has fixed thereon a pair of pins 123, and 124, arranged to project into the inclined grooves in the sleeve whereby relative rotation of said members causes translation of the control member along the shaft.

Means for actuating the pinion 115 from the control member 122 is provided comprising an overrunning clutch connection formed by rollers 125 seated in an enlarged portion 126 of the control member and adapted to cooperate with a driven clutch member 127 which is splined on the hub 128 of pinion 115. The longitudinal movement of the clutch member 127 is transmitted yieldingly to pinion 115 through a spring 129, the spring being maintained under initial compression by a retaining ring 131 fixed on the end of the pinion hub. A cover plate 132, crimped in the end of the control member serves to enclose the clutch mechanism and to retain the clutch member 127 in the end of the control member.

Means for holding the pinion 115 in mesh with the engine gear 116 is provided in the form of a detent pin 133 mounted in the shaft 110 and sleeve 117 with freedom for radial sliding movement so as to engage the interior of the control member. The rear of the control member is beveled as shown at 134, and the pin 133 is so located that when the parts are in cranking position, the pin engages the beveled portion of the control member as shown in Fig. 13, so as to prevent retrograde motion of the control member.

Means for actuating the detent 133 is provided, comprising a plunger 135 slidably mounted within the shaft 110 and having a beveled portion 136 adapted to engage a corresponding beveled portion 137 on the inner end of the detent. A rod 138 corresponding to the actuating rod 93 of Figs. 7 to 9 inclusive is arranged to actuate the plunger through a yielding connection comprising the compression spring 139. It will be understood that the rod 138 may be operated in the same manner as the rod 93 so that further illustration of said operating means is deemed unnecessary.

In the operation of this embodiment of the invention, starting with the parts in the positions illustrated in Fig. 12, acceleration of the power shaft 110 by the starting motor causes the sleeve 117 to rotate and thereby traverse the control member 122 to the right by means of the pin and slot connection therebetween in the manner previously described. When the pinion 115 is meshed with the engine gear 116, the detent pin 133 is brought into engagement with the beveled surface 134 of the control member 122 under the action of plunger 135 as illustrated in Fig. 13. Further rotation of the power shaft 110 is transmitted through the control member 122 and clutch rolls 125 to the clutch member 127 and pinion 115 whereby the engine gear is rotated to crank the engine.

When the engine fires, the acceleration of the engine gear causes the pinion 115 to overrun the

control member but as long as pressure is maintained by the rod 138 on the plunger 135, the pin 133 prevents demeshing movement of the control member and pinion.

When the engine is reliably self-operative the operator releases the rod 138 and deenergizes the starting motor whereupon the power shaft 110 decelerates. The plunger 135 is withdrawn from the detent 133, and when the speed of rotation of the power shaft is reduced sufficiently, drag of the overrunning clutch, and the inertia of the parts overcomes the centrifugal force acting on the detent pin so that the pin is cammed down into the sleeve 117 and the parts returned to their idle position.

Although certain embodiments of the invention have been shown and described in detail, it will be understood that other embodiments are possible and that variations in the design and arrangement of the parts may be made without departing from the spirit of the invention as defined in the claims appended hereto.

What is claimed is:

1. In an engine starter drive a power shaft, a pinion slidably journaled thereon for movement into and out of mesh with a gear of an engine to be started, means for actuating the pinion including a control member loosely mounted on the shaft, means for imparting rotary and longitudinal movement from the control member to the pinion, said control member having an inclined slot, a pin diametrically traversing the shaft and said slot to form an inclined connection between the shaft and control member, a detent spring on the shaft adapted to engage the control member when in idle position and yieldingly oppose movement thereof, and unitary means for immobilizing the pin and the spring with respect to the shaft.

2. In an engine starter drive a motor shaft, a control member slidably journaled thereon and having an inclined driving connection therewith, a pinion having an overrunning clutch connection with the control member and movable thereby into and out of mesh with a gear of an engine to be started, and means under the control of the operator for holding the pinion in mesh with the engine gear.

3. In an engine starter drive a motor shaft, a control member slidably journaled thereon and having an inclined driving connection therewith, a pinion having an overrunning clutch connection with the control member and movable thereby into and out of mesh with a gear of an engine to be started, and means energized concomitantly with the actuation of the motor shaft for preventing retrograde longitudinal movement of the control member.

4. In an engine starter drive a motor shaft, a control member slidably journaled thereon and having an inclined driving connection therewith, a pinion having an overrunning clutch connection with the control member and movable thereby into and out of mesh with a gear of an engine to be started, means including a detent movable by centrifugal force into engagement with the control member to prevent movement thereof in a direction to demesh the pinion and means energized concomitantly with the actuation of the motor shaft for holding said detent in operative position.

5. In an engine starting system, a starting circuit including a motor and a starting switch, said motor having a power shaft, a pinion slidably journaled on the power shaft for movement into

and out of mesh with a gear of an engine to be started, means including an overrunning clutch actuated by the power shaft for shifting the pinion into mesh with the engine gear and thereafter rotating the pinion to crank the engine, means for holding the pinion in mesh with the engine gear, and unitary means for closing the starting switch and actuating the holding means.

6. In an engine starting system, a starting circuit including a motor and a starting switch, said motor having a power shaft, a pinion slidably journaled on the power shaft for movement into and out of mesh with a gear of an engine to be started, means including an overrunning clutch actuated by the power shaft for shifting the pinion into mesh with the engine gear and thereafter rotating the pinion to crank the engine, detent means for holding the pinion in mesh with the engine gear, and unitary means for closing the starting switch and actuating the holding means, said actuating means including a yielding connection which permits the starting switch to close prior to movement of the detent into holding position.

7. In an engine starting system a starting motor having a hollow power shaft, a control member slidably journaled on the power shaft and having an inclined connection therewith for longitudinal movement thereon and rotary movement thereon and therewith, a pinion having an overrunning clutch connection with the control member and movable thereby into and out of mesh with a gear of an engine to be started, said control member having an interior annular shoulder, a detent mounted in the shaft for radial movement into engagement with said shoulder to prevent longitudinal movement of the control member in a direction to demesh the pinion, and means including a plunger slidably mounted in the power shaft and engageable with said detent to hold the detent in operative position.

8. In an engine starting system a starting motor having a hollow power shaft, a control member slidably journaled on the power shaft and having an inclined connection therewith for longitudinal movement thereon and rotary movement thereon and therewith, a pinion having an overrunning clutch connection with the control member and movable thereby into and out of mesh with a gear of an engine to be started, said control member having an interior annular

shoulder, a detent mounted in the shaft for radial movement into engagement with said shoulder to prevent longitudinal movement of the control member in a direction to demesh the pinion, a plunger slidably mounted in the power shaft and engageable with said detent to hold the detent in operative position, manually controlled electro-magnetic means for closing said starting switch and a yielding operative connection between said electro-magnetic means and plunger.

9. In an engine starter drive a hollow power shaft, a sleeve fixed thereon having an inclined groove formed therein, a control member having a pin fixed therein and slideable in said groove, a pinion slidably journaled on the power shaft having an overrunning clutch connection to the control member and movable thereby into and out of mesh with a gear of an engine to be started, a detent pin mounted in said shaft and sleeve for radial sliding movement into engagement with said control member to prevent demeshing movement thereof, and a plunger slideable axially in the shaft into engagement with the detent pin to hold it in operative position.

10. In an engine starter drive a hollow power shaft, a sleeve fixed thereon, a control member loosely mounted on the sleeve and having an inclined connection therewith, a pinion slidably journaled on the power shaft, means including an overrunning clutch for actuating the pinion from the control member, a detent mounted in the sleeve and movable into engagement with the control member to prevent demeshing movement thereof, and means for holding the detent in operative position.
